Charles O. Gooding.

SACKETT & WILHELM CO. INC.

UNITED STATES PATENT OFFICE.

MABEL H. SLATER, OF WEBSTER, MASSACHUSETTS.

SUN-DIAL AND COMPASS.

1,258,160.

Specification of Letters Patent.

Patented Mar. 5, 1918.

Application filed September 25, 1916. Serial No. 121,920.

To all whom it may concern:

Be it known that I, MABEL H. SLATER, a citizen of the United States, residing at Webster, in the county of Worcester and 5 State of Massachusetts, have invented new and useful Improvements in Sun-Dials and Compasses, of which the following is a specification.

This invention relates to a combined sun 10 dial and compass.

The object of the invention is to provide a small, compact and simple instrument constructed and arranged to be carried in the pocket but which is adapted to be used to 15 determine either the points of the compass or the hours of the day.

The invention consists in the combination and arrangement of parts set forth in the following specification and particularly 20 pointed out in the claim.

Referring to the drawings:

Figure 1 is a front elevation of an instrument embodying my invention.

Fig. 2 is a section taken on the line 2—2 25 of Fig. 1.

Fig. 3 is a detail section taken on the line 3—3 of Fig. 1, illustrating the two positions of the style of the sun dial and the means for maintaining said style in either of said 30 positions.

Like numerals refer to like parts in all views of the drawings.

In the drawings, 5 is a case, preferably of a design similar to that of a watch case, 35 thus rendering the same more suitable for carrying in the pocket. A dial 6 is mounted upon the case 5 in any suitable manner, said dial being constructed of suitable transparent material, such as glass, and having 40 graduations 7, 7 upon the face thereof. The dial 6 preferably constitutes a closure for the case 5 or the equivalent of the crystal of a watch.

A magnetic needle 8 is pivotally mounted, 45 preferably within the case 5, adjacent to the inner face of said dial 6 and completely incased to prevent moisture from gaining access thereto. Furthermore, said magnetic needle 8 is mounted in the usual manner 50 upon a pivot 9 so as to turn freely and permit the same to be turned to its normal position by the magnetic forces exerted thereon.

Marks indicating the points of the compass 55 are provided in said case 5, preferably upon a dial 10 arranged at the bottom of

said case but adjacent to and parallel with the plane of rotation of the needle 8 and also parallel with the dial 6.

A stem 11 is preferably attached to one 60 side of said case 5 to provide a support for means adapted to be operated to hold the needle in a fixed position within the case when the compass is not in use or when the same is being carried in the pocket. The 65 instrumentalities for clamping the needle form no part of this invention, therefore a description thereof is not believed to be necessary.

Arranged adjacent to the outer face of the 70 dial 6 is an angle plate 12 known to those skilled in the art as a style or gnomon. The style 12 when in its operative position is disposed substantially at right angles to the face of the dial 6 and in a predetermined 75 position on said dial with respect to the north and south points of the compass and the edge 13 of said style, is inclined upwardly from the dial at a predetermined angle to coöperate with the graduations 7 80 on the face of the dial 6, which correctly determine the time of day by the shadows projected upon the dial by said style in intercepting the sun's rays.

The face of the dial 6 is also provided 85 with a semi-transparent area 14 which is arc shaped to include the graduations 7, said semi-transparent section being preferably formed by grinding the portion of the surface of said dial included within the area 14. 90

This semi-transparent section is provided for the purpose of distinguishing between the shaded and light portions of the dial, the dividing line of which would be almost imperceptible upon a polished glass surface. 95 By combining the dial 6 and style 12, which form a sun dial with the compass embodying the needle 8 and dial 10, the correct position of the style 12 may be easily determined when the case 5 is placed upon a horizontal 100 table and the needle 8 released so that the magnetic forces will turn said needle into its correct position, after which said case 5 may be revolved until the style 12 points in the right direction. 105

The style 12, in its normal position, occupies considerable space and is not in a convenient form to be placed in the pocket, therefore said style has been pivotally mounted so as to permit it to be swung from 110 its normal position with respect to the face of the dial 6 into a position lying substan-

tially parallel with said dial and against its face.

To accomplish this result, said style has a cylindrical member 15, formed adjacent to the outer end thereof, which cylindrical member is journaled to rotate in a bearing 16 attached to the side of the case 5 adjacent to said stem 11. The lower edge of the style 12 is rounded at 17 and preferably lies along the upper face of the dial 6, permitting said style to be rotated from its normal to its folded position without interference and at the same time constituting a support therefor.

15 The outer end of the cylindrical member 15 has a plate 18 attached thereto having notches 19 and 20 in its periphery said notches corresponding to the two positions of said style. A resilient member or detent 20 21 is mounted in the stem 11 to occupy the notches 19 and 20 and to yieldingly position said style in its two positions.

Stops 22 and 23, disposed adjacent to the notches 19 and 20 respectively, are provided for the purpose of limiting the movements of said style. To still further enlarge the usefulness of this instrument, the central portion of the dial 6, which central portion is of little use in connection with the com-

pass or the sun dial, is made into a mirror 24.

Having thus described my invention what I claim and desire by Letters Patent to secure is:

In combination, a case, a magnetic needle pivotally mounted in said case, a style pivotally arranged to rock about an axis disposed substantially parallel with the plane of rotation of said magnetic needle, said style being movable from a position substantially parallel with said plane to a position substantially at right angles thereto, a plate secured to said style, said plate having two notches in the periphery thereof corresponding with the two positions of said style, and a resilient member attached to said casing, adapted to occupy one or the other of said notches to yieldingly maintain said style either in its position substantially parallel with said plane of rotation or substantially at right angles thereto.

In testimony whereof I have hereunto set my hand in presence of two subscribing witnesses.

MABEL H. SLATER.

Witnesses:

CHARLES S. GOODING,
SYDNEY E. TAFT.
